UNITED STATES PATENT OFFICE

151,961

DESIGN FOR A BED

Anthony J. Buckner, New York, N. Y., assignor to Grosfeld House, Inc., New York, N. Y.

Application March 29, 1947, Serial No. 138,045

Term of patent 7 years

(Cl. D5—4)

To all whom it may concern:

Be it known that I, Anthony J. Buckner, a citizen of the United States of America, residing in New York city, county of New York, and State of New York, have invented a new, original, and ornamental Design for a Bed, of which the following is a specification, reference being had to the accompanying drawing, forming part thereof, wherein the figure is a front perspective view of a bed, showing my new design.

I claim:

The ornamental design for a bed, substantially as shown.

ANTHONY J. BUCKNER.
